US00D794160S

(12) **United States Design Patent** (10) **Patent No.:** **US D794,160 S**
(45) **Date of Patent:** **** Aug. 8, 2017**

(54) **FLOATING SOLAR STERILIZER**

(71) Applicant: **Compurobot Technology Company**,
Dongguan (CN)

(72) Inventor: **Wing-Tak Hui**, Hong Kong (CN)

(73) Assignee: **COMPUROBOT TECHNOLOGY
COMPANY**, Dongguan (CN)

(**) Term: **15 Years**

(21) Appl. No.: **29/573,239**

(22) Filed: **Aug. 3, 2016**

(51) LOC (10) Cl. **23-01**

(52) U.S. Cl.

USPC **D23/207**; D23/208

(58) **Field of Classification Search**

USPC D23/207, 208, 209; 422/265; 210/198.1

CPC C02F 1/24; C02F 1/688

See application file for complete search history.

(57) **CLAIM**

The floating solar sterilizer, as shown and described.

DESCRIPTION

FIG. 1 is a perspective view of a floating solar sterilizer;
FIG. 2 is a front view of a floating solar sterilizer;
FIG. 3 is a rear view of a floating solar sterilizer;
FIG. 4 is a left-side view of a floating solar sterilizer;
FIG. 5 is a right-side view of a floating solar sterilizer;
FIG. 6 is a top plan view of a floating solar sterilizer; and,
FIG. 7 is a bottom plan view of a floating solar sterilizer.
